UNITED STATES PATENT OFFICE.

GEORGE J. COOKE, OF CHICAGO, ILLINOIS.

GAS COMPRESSOR.

Application filed June 23, 1924. Serial No. 721,632.

To all whom it may concern:

Be it known that I, GEORGE J. COOKE, a citizen of the United States, residing at Chicago, in the county of Cook and State of Illinois, have invented a certain new and useful Improvement in Gas Compressors, of which the following is a specification.

This application is in some respects a division of my prior application, Serial No. 10 629,392, filed April 2, 1923. In other respects, it is an improvement thereon.

This invention relates to refrigerating apparatus of the type employing a refrigerating medium which, in the operation of the 15 apparatus, is caused to become compressed and thereafter condensed to reduce it to liquid condition, and in such liquid condition is expanded into a conduit for effecting, in the expanding thereof, the extraction 20 of heat from the atmosphere or liquid, such as brine, as the case may be, in contact with the walls of the conduit, and is thereafter re-compressed and recondensed for again producing the refrigerating effect.

25 The primary object is to provide a novel, simple and inexpensive construction of apparatus of the character above stated, which may be operated economically and danger of impairment of which will be reduced to the minimum. A further object is to provide for the production of any desired degree of refrigeration, whether it be a high, low or any desired intermediate temperature, within the limits of the refrigerating medium 30 employed, without requiring adjustment of any of the parts of the apparatus for the different degrees of refrigeration, and without danger of flooding the system. A still further object is to provide an apparatus 35 which may, at will, be used for effecting the refrigerating function in connection with different characters of work being performed, as for example refrigerating a domestic ice box and an ice cream freezer, 40 which require different degree of refrigeration, and without danger of flooding the apparatus with refrigerating liquid thereby preventing accidents and rendering the apparatus operable at the minimum expense 45 and attention; and other objects as will be manifest from the following description.

Referring to the accompanying drawings:

Figure 1 is an external side elevation and Figure 2 is a plan view of mechanism illus-

trating this invention in its preferred form. 55

Figure 3 is a transverse section on the irregular line 3—3 of Figure 2.

Figure 4 is a vertical sectional elevation of a combined compressor and condenser embodying certain features of the invention. 60

Figure 5 is a section taken at the line 5—5 on Figure 4, as seen in the direction of the arrows.

Figure 6 is a plan section taken at the line 6—6 on Fig. 5. 65

Figure 7 is a reduced size end view of the machine taken from the left of Figures 1 and 2.

The combined compressor and condenser, the details of which are shown more particularly in Figures 4, 5 and 6, involves in the particular form thereof illustrated, a base 10 surmounted centrally by a hollow crank case casting 12, there being formed in the top of the casting an oil retaining 70 ditch or trough 14, adapted to confine any oil or other liquid which may escape from the compressor. Inside the casting 12 are walls 16 defining a crank-case chamber 18, and compartments 20 and 22 provided with 75 removable closures 24 and 26, respectively. Compartment 22 is provided with a drain passage 28 leading into crank case chamber 18. The apparatus now being described is intended for operation upon any suitable refrigerant, such as, ammonia, though any other suitable material may be used, the compartment 20 serving as a receiver for the 80 condensed refrigerant and the compartment 22 serving as a receiver for lubricant and 85 into which compartment the gas to be compressed flows, on its way to the compressor, this compartment, to this end, being shown as communicating, at the inlet 30, with a pipe 32 leading to the outlet of the refrigerating coil, hereinafter referred to. The cylinder of the compressor represented at 34 is provided adjacent its lower end with an annular, peripheral flange 36, resting upon annular washer 38 on the top of the casting 12, being secured in place by suitable lag-screws 40. The lower portion of the cylinder 34 extends at its portion 42 into the reduced upper end portion 44 of the crank-case 18. The piston 46 of the compressor, reciprocal in the cylinder 34, is connected by pitman 48 with a crankpin 49, eccentric to crank-shaft 50, journaled at its 90

100
105
110

opposite ends in the opposite end walls of the crank-case 18. Crank shaft 50 is provided at its outer end with a drive pulley 52 for driving the compressor. The shaft ends are the portions thereof at which it is journaled in the walls of the compartment by conventional, anti-friction devices 54 and 56. Anti-friction device 54, specifically a ball bearing, is operatively carried by a box 58, 10 screw-threaded at 60 into a suitable opening in the side of crank-case casting 12, and bears against washer 62. Inside this box 58 and behind the anti-friction device 54 is a seal ring 64 and washers 66 and 68 fully 15 shown, described and claimed in my prior patent application, Ser. No. 620,922, filed February 24, 1923, the washer and ring combining and operating to certainly prevent the passage of any lubricant or ammonia 20 gas or the like from chamber 18 along the surface of shaft 50 or between ring 64 and abutment 70 in box 58 out of the compressor mechanism. This ring and washer device does not, however, prevent the passage of 25 lubricant from the crank-case 18 and the anti-friction ball mechanism 56 into an oil chamber 72 in box 58, and about ring 64 from which oil chamber a conventional form of oil conveying washer or wiper 74 carries 30 the oil up over the seal ring 64 as is desirable for the successful operation of the device.

The opposite anti-friction mechanism 54, carrying the opposite end 50^a of shaft 50 is similarly mounted in a box 76 screw-threaded at 78 into the adjacent wall of crank-case casting 12 against washer 80. This box 76 is provided in its central portion behind the anti-friction device 54 with 40 an oil chamber 82 like chamber 72 in box 58.

In order to provide means for forcing the shaft 50 and attached mechanism to the right as viewed in Figure 4, in order to secure sufficient bearing of the seal ring 64 against the abutment 70, as heretofore described, shaft end 50^a is provided at its end with a cylindrical recess 84 containing a compression spring 86 bearing at its inner end on a washer 88 preferably but not necessarily resting on an anti-friction ball 90 and bearing at its outer or left hand end on a washer 92 sliding on a post 94 projecting from the inside of the back or left hand wall of box 76 axially of shaft 50. This washer 92 and the spring 86 are retained in operative position when the entire shaft mechanism is removed from the compressor or when box 76 is removed from the compressor wall while the shaft is still in the machine by means of a nut 96 screw-threaded on the end 50^a of shaft 50 but perforated as shown in Figure 4 to freely slip over post 94. In the operation of this mechanism just described, the spring 86, acting 60 on washer 92 as a stationary base always

tends to move the shaft 50 to the right as viewed in Figure 4, thus forcing the seal ring 64 against abutment 70 of box 50^a and making a proper oil and gas seal about that portion of shaft 50 which necessarily protrudes from the compressor case in order to permit of its carrying driving pulley 52. 70

The wall of the crank-case 18, adjacent the upper extremity of the compartment 22, contains a port 98 opening into this compartment and also into a channel 100 provided in the outer periphery of the lower end of the cylinder casting 34, this channel extending around the cylinder 34 and communicating with passage 102 in the wall of 80 the casting 34, forming the gas inlet, opening into the cylinder bore 103 interior of the cylinder casting 34, as shown in Figures 4 and 5. Inlet 102 is opened to the interior 103 of the cylinder only during 85 the final movement of the piston to its lowermost position, and in such final lowermost position, the top of the uppermost piston ring does not extend below the lowermost edges of the inlet. 90

The apparatus now being described also comprises a condenser element shown in the form of a coil 104 surrounding the cylinder 34 and housed within a casing member 106, resting at its upper end on washer 108 in 95 annular notch 110 in the upper end of cylinder 34 and resting at its bottom on annular washer 112 on the top of upper flange 114 of casting 12, being drawn into tight 100 connection on both washers through lag screws 116 or the like entering the flange 114. The lower end of the condenser coil 104 communicates with an opening 118 located in the top of the compartment 20 whereby the condenser discharges into this 105 compartment. The upper end of the condenser terminates in a coupling 120 by which it is connected with a discharge outlet 122 of a chamber 124 of greater diameter than piston 46 contained in the upper 110 end of the cylinder 34. This chamber communicates with the interior 103 of the cylinder 34 by a port 126 in plate 128, closing the top of the cylinder, and the port being controlled by an outwardly-opening check valve 130 located in an enlargement in plate 128 above port 126. The valve 130 is provided with a spring 132, releasably holding the valve to its seat. The upper end of the spring 132 extends into a recess 134 provided in the under side of a valve plug 136 which screws into the threaded, upper end of the chamber 134, this plug being provided with an annular flange at its periphery which screws down upon an annular washer 140 let into a suitable recess, bordering chamber 124 formed in the upper end of cylinder casting 34. The plug 136 contains a passage 142 therethrough which 115 opens at one end into the chamber 124 and 120

at its outer end to the atmosphere, this passage being provided with a valve device 144 adapted to control the flow of gas through the passage 142. The valve device 144 is a 5 purge valve and is provided for the purpose of affording a vent for such foreign gases as may exist in the apparatus, it being understood that after such gases are vented from the system, this valve is manually closed by applying a wrench to non-circular bolt head 146.

Plate 128 forming the bottom of chamber 126 is detachably held in place at the upper end of the piston chamber of the cylinder 15 casting 34 by a nut-like plate 148 engaging the screw threaded wall 150 of chamber 124. The upper projecting part 152 is non-circular, or the like, so as to be engaged by a wrench to thereby rotate plate 148 over 20 said threads 150. Member 148 is centrally perforated, as shown, to allow free movement of spring 132 there-through.

By removing members 128, 148 and 136 in obvious manner, piston 46 can in assembling the mechanism be inserted in and removed from the upper end of the cylinder 34. Furthermore, by thus providing a piston bore 103 for the cylinder initially open at both ends, the bore can be more easily, 30 cheaply and accurately machined than where the upper end is cast closed as in the construction of said prior application.

The receptacle 20 for the condensed gas and from which the liquefied gas is conducted to the refrigerating coil, not shown, 35 is provided with an outlet 154.

In order to use the machine of this invention, heretofore described, in a refrigerating system, it is necessary that power 40 be applied by means of a belt 156 or the like and, as refrigerating apparatus of this class is now sold for installation in private residences and the like, the method of efficiently driving belt 156 and consequently 45 the machine of this invention is of importance. The problem is solved in this invention by providing base 10 with a suitably disposed extension 10^a, provided in its upper portion with a motor carrying platform 50 158 journaled on horizontal pivots 160, so positioned between the electric motor mounted on the platform 158 and pulley 52 that the weight of the motor 162 will always tend to create a tension on belt 156 55 drawing it tight over pulley 52 and motor pulley 164. This construction insures efficient operation of the motor 162 in driving pulley 52 and consequently the refrigerating machine. If for 60 any reason it is desired to mechanically disconnect the motor from the compressor, all the operator has to do is to take hold of platform 158 and move it in a counter clockwise direction about pivots 160; or, in other 65 words, raise motor 162 thereby rendering

belt 156 loose enough so that it can be readily removed from the pulleys over which it normally travels.

It will be readily understood from the foregoing description that in the operation 70 of the compressor, when it is driven by the motor 162, gas passes from pipe 32 into compartment 22 from which it is sucked through port 98 and passage 102 into the interior 103 of cylinder 34 above piston 46, 75 thus filling the vacuum which was created in space 103 by the previous downward movement of piston 46 to the position shown in Figures 4 and 5. On the upward stroke of the piston, gas thus introduced into the 80 cylinder is compressed and forced out through the port 126, valve 130 yielding to permit this, the gas thence passing into the condenser coil 104 wherein it is cooled by water or other cooling liquid continually 85 conventionally introduced into and removed from chamber 166 about the coil through pipes not entering into this invention and therefore not shown. Gas thus condensed in coil 104 flows into compartment 20 from 90 which it is conducted by pipe 154 to the refrigerating work, not entering into this invention and therefore not shown, from which point it returns in expanded condition to pipe 32 and thence back to chamber 95 22 where it is re-pumped through the machine.

It will also be noted that by constructing a machine in accordance with my invention, it is rendered very compact and of light 100 weight, inexpensive to manufacture, because of fewer parts, capable of being operated economically and highly satisfactorily; and affords capabilities which heretofore have either involved difficulties in the operation 105 of apparatus or required separate apparatus for their accomplishment.

It will be noted by providing the passage 102 as explained, oil which may be carried up into the cylinder bore 103 above 110 the upper piston-ring therein will flow by gravity through the passage 102 back to the chamber 22 which in practice would be partially filled with lubricating oil, it being understood that by reason of the communication 115 28 between the crank case and this chamber at the lower end of the latter the oil will extend to substantially the same level in the crank case wherein it is subjected to the action of the operating mechanism therein and serves to lubricate the piston by splash feed. Furthermore, the proportioning of the parts so that the top upper side of the upper piston-ring is never below the lower edges of the outlets 102, 120 where open into the cylinder bore 103, is of advantage inasmuch as the gas in entering the cylinder bore 103 and in becoming compressed upon the upward stroke of the piston, swirls in the cylinder and forces oil 125 130

which may be on top of the said piston-ring and piston head, out through the port 102 from which it gravitates into the chamber 22 thus avoiding inter-mixture of the oil with the refrigerating medium being compressed.

It has been found in practice that by constructing the cylinder 34 with the inlet thereto so disposed that oil flowing to the inlet will gravitate therethrough away from the cylinder, and providing the piston as described, the gas discharged from the cylinder is free of lubricating oil, unless some impairment of the apparatus occurs, the chamber 20 being provided primarily as a safety feature to separate oil from the liquefied refrigerant in the event that any oil does discharge with the gas into the condenser.

It will be noted that compartments 20 and 22 do not extend to the bottom of crank case 18 with the result that a proper amount of oil in the bottom of the crank case can foam without rising into the cylinder and, it will be noted that by reason of the disposition of the chambers 20 and 22, and crank-case 18, the gas returning to the receptacle 22, from the refrigerating coil, the gas being in a relatively cold state, operates to exert a cooling effect upon all three of these chambers, the chamber 22 serving to receive any oil that may be picked up by the gasified refrigerant in its passage thereto, which oil precipitates and flows out through passage 28.

It will be noted that the gas chamber 22 is of relatively large proportions, and that by reason of its close proximity to the cylinder 34 and the provision of the ports connecting these parts, a constant supply of gas to the cylinder 34 and of a volume sufficient to cause the apparatus to perform in a highly desirable manner, is effected.

While I have illustrated and described a particular construction embodying my invention, I do not wish to be understood as intending to limit it thereto as the same may be variously modified and altered without departing from the spirit of the invention.

The upper end of passage 30 is in chamber 22 preferably provided with an extension pipe 170 having its upper end open to gaseous refrigerant material while its side walls retain oil adjacent to passage 28 in the bottom of chamber 22 and thus prevents the oil from traveling out of passages 30-32. The base of this pipe 170 is preferably surrounded with porous material—such as waste 174—to check the spouting of any oil which may be driven to chamber 22 from chamber 18.

In the same manner, the upper end of passage 154 in chamber 20 is preferably provided with an extension pipe 176 designed to retain oil 178 in chamber 20 and prevent its passing out through pipe 154. In actual practice, oil 178 only collects in this chamber

when the machine is new and under these conditions it is removed by unscrewing the plug 180 in obvious manner.

Attention is called to the fact that in making the exterior casing of the machine as shown and described, the device is a one-piece combination of crank case, refrigerant gas chamber, and refrigerant liquid receiver. Further, by making the exterior plane of the case rectangular instead of round, as in present constructions, economy of cost is attained due to a reduction in weight and space occupied by the machine.

Having thus described my invention, what I claim as new and desire to secure by Letters Patent is:

1. In a structure of the character set forth, the combination of a compressor comprising a crank-case, a cylinder, a piston operating in the cylinder, and piston driving mechanism extending into the crank case, a chamber for lubricating oil extending to one side of said crank-case and communicating with the latter below the level of the oil in said chamber, said cylinder containing an inlet port and an outlet port, said inlet port communicating with said chamber, and said chamber containing an inlet through which the gas to be compressed passes into said chamber and thence into said cylinder to be acted on by said piston.

2. In a structure of the character set forth, the combination of a compressor, chambers located at opposite sides of said compressor, said compressor containing an inlet and an outlet in communication with said chambers, respectively, one of said chambers being a gas-inlet-and-lubricating-oil chamber in communication with the source of gas to be compressed and also communicating with the compressor below the gas outlet from this chamber to the compressor, and the other of said chambers being a liquefied gas receiver.

3. In a gas compressor, a crank case, a chamber above the bottom of said crank case through which gas to be compressed is adapted to pass and in which a precipitate of said gas is adapted to collect, said chamber being in communication with said crank case whereby the precipitate will flow from said chamber into the crank case.

4. In a gas compressor, a crank case, a chamber through which gas to be compressed is adapted to pass and in which a precipitate of said gas is adapted to collect, said chamber being located at the side of and separated from the crank case by a wall of the latter, and said wall having a passage therethrough providing communication between the crank case and said chamber.

5. In a gas compressor including a crank case, a cylinder and a piston; means defining a passage for conducting gas to be compressed to said cylinder, said passage open-

ing at its upper end into said cylinder and extending continuously downward and communicating with said crank case.

6. In a compressor including a crank case, 5 a pair of chambers located at different sides of said compressor and communicating respectively, with an inlet to and an outlet from said compressor, the chamber in communication with the inlet to said compressor also being in communication with said crank case.

7. In a compressor, a pair of chambers located at different sides of said compressor and communicating, respectively, with an 15 inlet to and an outlet from said compressor, the chamber in communication with the outlet from said compressor being located below said outlet.

8. In a compressor, a cylinder having an 20 enlarged bore at one end thereof providing a chamber having an exit opening, a piston operable within said cylinder to force fluid through said chamber to said exit opening, a plate of greater diameter than the 25 main cylinder opening located in said chamber and having a valve port therein, a valve cooperating with said port to control the flow of fluid through said chamber, and a locking plate for securing said first mentioned plate within said chamber.

9. In mechanism of the class described, a cylinder initially open at both ends for the reception of a piston, one end of said cylinder having an enlarged bore forming a 35 chamber having an inlet thereto and an outlet therefrom, a piston operable within said cylinder to cause fluid to flow through said chamber, a plate of greater diameter than the main cylinder opening located within 40 said chamber and disposed across the adjacent end of the main cylinder opening, said plate having a port therein, a valve cooperating with said port to control the flow of fluid through said chamber, a per- 45 forated plate in threaded engagement with the wall of said chamber to detachably lock said first mentioned plate therein, and a de-

tachable closure plug for the outer end of the chamber.

10. In mechanism of the class described, 50 a cylinder initially open at both ends for the reception of a piston, one end of said cylinder having an enlarged bore forming a chamber having an inlet thereto and an outlet therefrom, a piston operable within 55 said cylinder to cause fluid to flow through said chamber, a plate of greater diameter than the main cylinder opening located within said chamber and disposed across the adjacent end of the main cylinder opening, 60 said plate having a port therein, a valve cooperating with said port to control the flow of fluid through said chamber, a per- 65 forated plate in threaded engagement with the wall of said chamber to detachably lock said first mentioned plate therein, a detachable closure plug for the outer end of the chamber, and a valve closing spring bearing at one end on said valve and at its other 70 end on said plug.

11. In mechanism of the class described, a cylinder initially open at both ends for the reception of a piston, one end of said cylinder having an enlarged bore forming a 75 chamber having an inlet thereto and an outlet therefrom, a piston operable within said cylinder to cause fluid to flow through said chamber, a plate of greater diameter than the main cylinder opening located within 80 said chamber and disposed across the adjacent end of the main cylinder opening, said plate having a port therein, a valve cooperating with said port to control the flow of fluid through said chamber, a per- 85 forated plate in threaded engagement with the wall of said chamber to detachably lock said first mentioned plate therein, a detachable closure plug for the outer end of the chamber, and a valve carried by said 90 plug for venting said chamber.

In witness whereof, I have hereunto subscribed my name.

GEORGE J. COOKE.
